UNITED STATES PATENT OFFICE.

JULES H. HIRT, OF EL PASO, TEXAS, ASSIGNOR, BY MESNE ASSIGNMENTS, TO ALLIS-CHALMERS MANUFACTURING COMPANY, A CORPORATION OF DELAWARE.

GAS-PRODUCER.

1,094,897.

Specification of Letters Patent. Patented Apr. 28, 1914.

Application filed February 14, 1910. Serial No. 543,723.

To all whom it may concern:

Be it known that I, JULES H. HIRT, a citizen of the United States, residing at El Paso, in the county of El Paso and State of Texas, have invented a certain new and useful Improvement in Gas-Producers, of which the following is a specification.

This invention relates to improvements in apparatus for making producer gas.

10 The object of the invention is to provide a producer for making gas from the combustion of a continuous stream of gas-forming combustible material mixed with air and the subsequent combination of gases 15 formed by the decomposition of steam or other moisture and recombination of the resulting gases with the gases evolved by the said combustion.

The admission of steam or other moisture 20 is for the purpose of adding hydrogen to the resulting gases and to secure a maximum percentage of carbon monoxid in the resulting gases. The process involved in the operation of the producer herein disclosed, 25 is claimed in Patent 1,039,398, granted Sept. 24, 1912.

The accompanying drawing illustrates one 30 of the embodiments of the invention and from a study of the same as described in the specification, a clear conception of the invention may be had.

The single figure of the drawing is a vertical section through the gas producer.

Referring to the drawing, the furnace 1 is 35 of any suitable configuration and is shown as vertically disposed with its interior preferably dome shaped at the top. This interior of the furnace is divided by a vertical wall 2 into the gas generating chamber 3 and 40 the narrow passage 4 leading at the bottom to the water seal 6. An inlet pipe 7 leads to the bottom of the gas generating chamber 3 and is upwardly directed. At its outer end a hopper 8 controlled by a gate 9 near its 45 bottom is in communication therewith, and a blowing means 10, such as a blower or fan, is directed into the open end of the inlet pipe 7 adjacent the communication from the hopper 8. A supplementary inlet pipe 15 50 communicates with the gas generating chamber 3 at a point slightly in advance of the point at which the inlet pipe 7 communicates

therewith, and is upwardly directed therein. At its outer end this inlet pipe 15 is similarly provided with a hopper 16 and with a blowing means 17. The inlet pipes 7 and 15 are connected by a pipe 71 at points adjacent the hoppers 8, 16 to permit of secondary supply through the primary inlet.

A steam pipe 11 is provided with valve 60 controlled branch pipes 12, 13, 14, and two of these branch pipes 12, 13, communicate with the gas generating chamber 3 at adjacent points slightly in advance of the point of communication of inlet pipe 15 with said 65 gas generating chamber 3. These branch pipes 12, 13, are also slightly upwardly directed to said gas generating chamber 3. Branch pipe 14 passes upwardly through wall 2 and at the highest point of the wall 70 2, communicates with the gas generating chamber 3. A supplementary valved gas starting inlet pipe 72 communicates with inlet pipe 7, said inlet pipe being forwardly directed at the point of communication. A 75 gas off-take pipe 5 communicates with the passage 4 at a point intermediate the gas generating chamber 3 and the water seal 6. This off-take pipe 5 passes to any point where it is desired to use the gas generated 80 in the gas producer.

Operation: A carbonaceous material having been introduced into the hoppers 8, 16, the blowing means 10 is caused to operate, directing a blast of air axially into the outer 85 end of inlet pipe 7 and past the discharge end of the hopper 8, the gate 9 having been adjusted to a suitable opening. Under these conditions, the ignition of the charge entering the other inlet pipe 7 having been effected in any suitable manner as by starting gas inlet 72, the gas-forming combustible material consisting of an admixture of finely divided carbonaceous material and air, will be carried upwardly through the gas generating chamber 3 and around the top of wall 90 2 down through passage 4 toward the off-take pipe 5. During its passage combustion will take place and the condition of completeness of such combustion will be determined by various conditions as to the extent 95 of opening of the hopper gate 9 and the blowing means 10; also upon other extraneous conditions, such as the temperature 100

- of the gas producer. Combustion having proceeded for a time, the gas producer will become highly heated especially in the upper part of the gas generating chamber 3. In order to control the extent of the temperature rise, steam is introduced through the various branch pipes 12, 13, 14, and these various points of introduction of the steam are designed to be at points of highest temperature. A chemical reaction takes place causing the disassociation of the elements of the steam or moisture into hydrogen and oxygen with a subsequent recombination of these gases wholly or in part with a gas-forming combustible material burning in the gas generating chamber 3. Free hydrogen, methane or marsh gas, carbon monoxide, and possibly carbon dioxide, will be some or all of the resulting gases.
- In order to reduce any carbon dioxide that may be formed within the gas generating chamber 3, a supplemental introduction of gas-forming combustible material is made through the inlet pipe 15 by using the blowing means 17 in combination with the gas controlled hopper 16 having therein carbonaceous material. This carbonaceous material being introduced at a point of high temperature within the gas generating chamber 3, unites with the carbon dioxide gas, if any there be, reducing same to carbon monoxide. The air introduced through the blowing means 17 combines with other carbonaceous material introduced thereby, the adjustment being such that the carbonaceous material is in excess.
- The gas-forming combustible material introduced either through the main inlet pipe 7 or the supplemental inlet pipe 15, may consist of liquid hydrocarbon and air instead of carbonaceous material and air. The ash formed by the combustion, and any excess of solid material introduced into the producer, pass down through the passage 4 into the water seal 6 from whence they may be externally removed without stopping the main operation of the producer and without opening up communication from within the same to the atmosphere.
- It should be understood that it is not desired to be limited to the exact details of construction shown and described, for obvious modifications will occur to a person skilled in the art.
- It is claimed and desired to secure by Letters Patent,—
1. The combination in a gas producer, of a free and open gas generating chamber formed therein, a downwardly directed passage smoothly communicating with the upper end of said chamber, a water seal into which said passage is directed, an off-take pipe, and an inlet for combustible material communicating with the lower end of said chamber and directed toward the point of communication of said passage with said chamber, whereby material discharged from said inlet is carried through said chamber and into said passage.
  2. The combination in a gas producer, of a free and open gas generating chamber formed therein, an upwardly directed inlet for combustible material communicating with the lower end of said chamber, a second upwardly directed inlet for combustible material communicating with said chamber at a point in advance of the first inlet, a downwardly directed passage smoothly communicating with the upper end of said chamber, a water seal into which said passage is directed, and an off-take pipe, said inlets being directed toward the point of communication of said passage with said chamber, whereby material discharged from said inlets is carried through said chamber and into said passage.
  3. The combination in a gas producer, of a free and open gas generating chamber formed therein, an upwardly directed inlet for combustible material communicating with the lower end of said chamber, a moisture inlet communicating with said chamber at a point in advance of the first inlet, a downwardly directed passage smoothly communicating with the upper end of said chamber, a water seal into which said passage is directed, and an off-take pipe, said inlets being directed toward the point of communication of said passage with said chamber, whereby material discharged from said inlets is carried through said chamber and into said passage.
  4. The combination in a gas producer, of a free and open gas generating chamber formed therein, an upwardly directed inlet for combustible material communicating with the lower end of said chamber, a second upwardly directed inlet for combustible material communicating with said chamber at a point in advance of the first inlet, a moisture inlet communicating with said chamber at a point in advance of the second inlet, a downwardly directed passage communicating with the upper end of said chamber, a water seal into which said passage is directed, and an off-take pipe, said inlets being directed toward the point of communication of said passage with said chamber, whereby material discharged from said inlets is carried through said chamber and into said passage.
  5. In a gas producer, a furnace having its interior divided into a free and open gas generating chamber and a free and open vertical passage in communication with said chamber at its upper end, an upwardly directed fuel inlet at the lower end of said chamber, a second fuel inlet leading into

said chamber and combining its flow with
that from said first mentioned inlet, a mois-
ture inlet leading to said chamber at the
junction of said chamber with said passage,
said moisture inlet being in advance of all
fuel inlets, and a gas offtake communicating
with said passage.

In testimony whereof, I affix my signa-
ture in the presence of two witnesses.
